UNITED STATES PATENT OFFICE

JOSEPH B. MURRAY, OF BROOKLYN, NEW YORK, ASSIGNOR, BY MESNE ASSIGNMENTS, TO AMERICAN RADIATOR & STANDARD SANITARY CORPORATION, A CORPORATION OF DELAWARE

RADIATOR

Application filed December 13, 1929. Serial No. 413,734.

My invention aims to provide certain improvements in radiators particularly of the type using a tube or similar vessel for the heating medium with corrugated sheets or 5 fins or similar extended area structure applied thereto so as to conduct the heat therefrom and transmit it to the air over a wide area.

The accompanying drawing illustrates embodiments of the invention.

Fig. 1 is a front elevation of a radiator of the Murray type;

Figs. 2, 3 and 4 are longitudinal sections of alternative designs for the open ends of 15 the tube;

Fig. 5 is a section on the line 5—5 of Fig. 1;

Fig. 6 is a similar section showing a modification;

Figs. 7 and 8 are respectively a partial elevation and a sectional view of a modified arrangement of the loop of the tube;

Fig. 9 is a plan of the right-hand end of Fig. 1.

Fig. 10 is a horizontal section of a modification.

A tube 1 for conveying steam or hot water (or cold brine, or the like, where the apparatus is to be used for cooling the air instead of heating it) is arranged in successive 30 lengths connected by a loop 2 with projecting ends 3 for attachment of the main pipes as described, for example, in certain previous applications of Thomas E. Murray, Ser. No. 709,080 filed April 26, 1924 (Patent No. 35 1,744,078, January 21, 1930), and others.

A pair of corrugated sheets are applied to opposite sides of the tube providing transverse fins 4 (Fig. 9) connected alternately at their outer ends by longitudinal plates 5 and 40 at their inner ends by longitudinal plates 6. The inner portions of the corrugations are recessed to embrace the tube and are clamped together around the tube by means of straps 7. The opposite straps are welded together 45 through the plates 6 and thus hold the corrugated sheets in close heat conducting contact with the tube, the welds being indicated at 8. The extended area of the corrugated sheets provides vertical passages through 50 which the air passes and is heated. A strong

draft is induced and causes a forcible circulation of the heated air throughout the room. This is a very efficient type of convection radiator. It may be made in a variety of styles and designs in detail, in all of which 55 the present invention is of value.

In radiators of this type it is preferred to use a copper tube for its high conductivity and for its flexibility. For the same reasons, and also to make it lighter and more economical, there are advantages in using as thin a tube as possible and my invention is directed particularly to this end.

The corrugated sheets or other style of fins are applied to the tube at short intervals 65 of the length of the latter, thus reinforcing it throughout most of its length. The finned portions of the tube, therefore, may be made of a gage so thin that it would not be feasible except for the reinforcing effect of the fins. 70 This reinforcement is particularly effective with the strap connections described. The straps are generally of steel or other comparatively stiff metal.

Where this reinforcement is lacking, I 75 propose to provide special reinforcements. Where a loop, such as 2 extends beyond the finned portion of the tube, it may be reinforced, for example, in the ways shown in Figs. 1 and 5 or in the alternative ways shown 80 in Figs. 6, 7 and 8.

According to Figs. 1 and 5, the reinforcement is also made to provide an extended heating area. Plates 9 are provided with recessed portions 10 embracing the loop of the 85 tube and with extensions forming outside fins 11 of the same height as the corrugated sheets. These plates 9 are welded or otherwise united to each other firmly at points 13 and 14 close to opposite sides of the tube 90 so as to ensure a good reinforcement and also a good heat conducting contact.

According to Figs. 7 and 8 similar plates 9 are fastened by means of straps 15 similar to those of Figs. 1 and 5 which are welded 95 through the plates 9 at opposite sides of the tubing.

Or as shown in Fig. 6, the loop 2 of thin tubing may be reinforced by a second tube 16 forced on to it before the formation of the 100

loop, the outer tube being also of copper or other metal which can be bent as required.

Where an end of the tube projects beyond the finned portion, it may be reinforced in the ways shown in Figs. 2, 3 and 4. In Fig. 2 it is swaged to form a portion 17 of extra thickness, which is preferably flared for the making of a good connection to the steam pipe.

According to Fig. 3 the end of the tube 3 is enlarged in diameter as at 18 and a reinforcing thimble 19 is inserted. Or, as in Fig. 4, the end may be reinforced by an outer sleeve 20 forced on the end of the tube.

Radiators made according to this invention show advantages of low cost and light weight secured by utilizing the reinforcing effect of the radiating structure throughout the greater part of the length of the tubing.

The shapes of the ends of the tubes, as shown in Figs. 2, 3 and 4, may be varied to suit the needs of the type of connection adopted. The tubular connection between the lengths of piping may be also varied from the simple curved shape shown at the right of Fig. 1, and may be reinforced in other ways than those above described. The loop or other connection may, in fact, be stiffened by embracing it between corrugated plates similar to those shown in the middle of the figure, and such corrugated plates may be thus separate from or continuous with those along the body of the radiator.

Fig. 10 is inserted to show the application of the improvement to a radiator using another style of fins to secure the extended area in contact with the air. The tube 3 in this case is similar to that of Fig. 2. Mounted on this tube are sheet metal fins 21 which may be of various shapes in elevation and which are fastened to the tube by means of flanges 22 surrounding openings through which the tube is forced. Clamping rings, solder or other fastening means may be used to ensure a good connection. These flanges embrace and strengthen the tube throughout the greater portion of its length. The end of the tube is thickened as at 17. The reinforced ends of the tubes are long enough to extend back into the radiator and to be enclosed by one or two of the fins. This is true for Fig. 1 as well as for Fig. 10. The strains on the end of the tube extend along its length to a considerable distance so that such reinforcement is advisable not only beyond the fins but within the fins to a slight extent.

What I claim is:

1. A radiator comprising a tube for the heating medium and fins in heat conducting relation thereto forming passages for the heated air, said tube being of cuprous metal too soft and flexible to hold its required shape in the radiator without reinforcement and said fins serving to reinforce the por-

tions of the tube to which they are applied sufficiently to hold it in the required shape, the tube having a portion extending beyond the fins and reinforced separately.

2. A radiator including in combination a tube for the heating medium, fins in engagement with the tube throughout the principal portion of its length, said tube being of metal too thin and flexible to hold its required shape in the radiator without reinforcement and said fins serving to reinforce the tube sufficiently to hold it in the required shape and providing an extended area for heating the air, an end of the radiator comprising a portion of the tube extending beyond said principal portion, and a separate reinforcement for substantially the full length of such extended portion.

3. A radiator including in combination a tube for the heating medium in substantially parallel straight lengths connected by an integral loop, said tube being of metal too thin and flexible to hold its required shape in the radiator without reinforcement, fins in engagement with said straight lengths serving to reinforce the tube sufficiently to hold it in the required shape and providing an extended area for heating the air, and a separate reinforcement for substantially the full length of such loop.

4. A radiator including in combination a tube for the heating medium in substantially parallel straight lengths connected by an integral loop, said tube being of metal too thin and flexible to hold its required shape in the radiator without reinforcement, fins in engagement with said straight lengths serving to reinforce the tube sufficiently to hold it in the required shape and providing an extended area for heating the air, and a separate reinforcement for substantially the full length of such loop, said reinforcements also having outward fins providing an extended area for heating the air.

5. The radiator of claim 3 the ends of the tube also being provided throughout their length with a reinforcement separate from that provided by the fins.

6. A radiator including in combination a tube bent to form successive straight portions and fins applied to the straight portions of the tube and serving to brace the same, the bent portion of the tube beyond the fins being separately reinforced throughout substantially its full length.

In witness whereof, I have hereunto signed my name.

JOSEPH B. MURRAY.
